UNITED STATES PATENT OFFICE.

CHARLES H. ANDERSON, OF SEATTLE, WASHINGTON.

CAR-BOLSTER.

941,691.

Specification of Letters Patent. Patented Nov. 30, 1909.

Application filed July 7, 1909. Serial No. 506,333.

To all whom it may concern:

Be it known that I, CHARLES H. ANDERSON, a citizen of the United States, residing at Seattle, in the county of King and State 5 of Washington, have invented a new and useful Improvement in Car-Bolsters, of which the following is a specification.

My invention relates to improvement in the construction of the companion bolsters 10 interposed between car-bodies and their trucks.

My object is to provide a construction of bolsters adapted for railway-cars generally and more especially for interurban electric- 15 railway cars, which, besides holding the truck and car-body together with desired security, will permit relative rocking of the parts within comparatively wide limits and, furthermore, contribute to safety and 20 smoothness of travel of the car-body during changes in angle either vertical or horizontal.

In the drawings—Figure 1 is a broken plan view of the car-body bolster; Fig. 2, 25 a view on irregular line 2—2 in Fig. 1 showing the body and truck-bolsters half in elevation and half in section; and Figs. 3 and 4, enlarge sections on lines 3 and 4 in Fig. 2.

The body-bolster 5, forming a part of the under frame of the car-body, is provided at its under side with a central semi-spherical ball-socket 6 and two segmental bearing- 30 plates 7, each in the arc of a circle drawn 35 from said socket and presenting smooth under faces slightly inclined toward the center of the bolster. The truck-bolster 8 is shaped at its ends, in practice, to fit the particular spring-supported securing means 40 therefor on the truck, which it is not thought necessary to illustrate. The bolster 8 is provided toward opposite ends with bearings 9 for frusto-conical rollers 10 registering with the bearing-plates 7, and has a central opening 11 surrounded at its upper end by a fixed truck center-plate 12 having an annular groove forming a lower ball-race member filled with balls 13. Journaled in the opening 11 is a king-bolt 14 having an annular 45 shoulder 15 and a head 16 of spherical form fitting the socket 6 in the body-bolster. Under the shoulder 15 is an annular bearing- 50

plate 17 having an annular groove 18 in its under side forming an upper race-member engaging the balls 13. The king-bolt is held 55 against removal by a nut 19.

The ball-bearing described permits ready turning of the king-bolt in the truck-bolster, whereby the car-body and truck may turn with reference to each other without material friction. The ball-and-socket construction 16, 6 forms the connecting joint between the bolsters and avoids any binding or material wear thereat from rocking of the car-body or during changes in angle, as 60 when the car starts upon or leaves an incline in the roadbed. The rollers 10 and segmental plates 7 form coöperating stops of an anti-friction nature limiting the rocking movements of the car-body. 70

My improved construction affords not only a most desirable pivotal connection between the car-body and truck contributing materially to the comforts of travel, but tends to lessen injurious results in the case 75 of certain accidents. For example, in the event of a collision between trains, causing one car to telescope another, a car-body in rising would readily leave its truck and be freed from the weight thereof, thereby tending 80 to diminish the force of impact between the car-bodies; furthermore, the freed truck would probably be caused to strike against the truck of the other car and thus further tend to diminish the force of the impact of 85 the car-bodies against each other.

What I claim as new and desire to secure by Letters Patent is—

1. In combination, a car-body bolster having a spherical socket in its under side, a truck-bolster, a king-bolt on the truck-bolster having a spherical head to fit said socket and an annular shoulder below said head, a grooved annular bearing plate below said shoulder, a grooved center plate on the truck-bolster, and balls interposed between said plates. 90

2. In combination, a car-body bolster, a truck-bolster, a king-bolt journaled in the truck-bolster, and a ball-and-socket bearing 100 connection between the king-bolt and body bolster.

3. In combination, a car-body bolster, a truck-bolster, a king-bolt and ball-bearing

therefor on the truck-bolster, and a ball-and-socket bearing connection between the king-bolt and body-bolster.

4. In combination, a car-body bolster, a truck-bolster, a ball-and-socket bearing connection between the said bolsters, one bolster having bearing surfaces on opposite sides of said ball-and-socket connection, and roll-

ers on the other bolster forming stops to engage said surfaces in the rocking of the car-body.

CHARLES H. ANDERSON.
